UNITED STATES PATENT OFFICE.

ALLEN NEWHALL, OF JERSEY CITY, NEW JERSEY.

POLISHING-MACHINE.

SPECIFICATION forming part of Letters Patent No. 224,214, dated February 3, 1880.

Application filed December 5, 1879.

To all whom it may concern:

Be it known that I, ALLEN NEWHALL, of Jersey City, in the county of Hudson and State of New Jersey, have invented an Improvement 5 in Turning and Polishing Machines, of which the following is a specification.

The object of this invention is to finish and polish vegetable-ivory buttons; but the mechanism may be used for finishing and polishing 10 other kinds of buttons, and also for boring the buttons, and for turning and finishing other articles.

I make use of a circular range of revolving spindles driven by a belt, and these spindles 15 are sustained in heads that are revolved progressively and carry around the circular range of revolving spindles. Each spindle is provided with a clamping-chuck that is opened by an end movement given to the spindle at a time 20 when it is not being revolved by the belt. At this time one button falls out or is removed, and another button is introduced. The clamping-spindles are brought around successively, and the turning, polishing, finishing, or boring 25 tools are upon a tool-holder that is moved with the main revolving head and pressed toward the buttons, and then springs back out of the way and returns to the place of beginning for the tools to act upon the next button as it is 30 brought around.

In the drawings, Figure 1 is an elevation of the machine. Fig. 2 is a plan, partially in section, at the line *x x*. Fig. 3 is a section at the end of the main shaft. Fig. 4 is an elevation representing the boring mechanism; and 35 Figs. 5 to 8 represent the buttons with the holes as bored progressively.

The frame *a* is of suitable character to sustain the parts. The main shaft *b* is supported 40 in bearings and provided with a wheel, *c*, that is moved around gradually by a screw or worm pinion, *c'*, upon a shaft, *c*², to which motion is given by the belt *d* or otherwise.

I have shown the shaft *d'* and pulley *d*² as 45 the devices to which the power is applied, and upon this shaft *d'* is a pulley, *f*, for the belt *g*.

The shaft *b* is provided with disks or heads *e e'*, of any suitable size, according to the number of spindles *h* that are received into such 50 heads and form a circular range.

The pulleys *h'* upon the spindles *h* are in

contact with the belt *g* during about half the revolution of the heads *e e'*, and hence are resolved by said belt; but during the other portion of the revolution of *e e'* the spindles do 55 not turn on their axes.

Each spindle is made with a clamping-jaw or chuck adapted to the article that is to be operated upon. In the drawings such chucks are shown as receiving button-blanks *i i*. 60

The chuck is made of spring-jaws *k*, passing into the cup-shaped or hollow end of the spindle *h*, and the spindle is mortised for the passage of a pin, *2*, that connects the jaws *k* with the ring *3* around the spindle. There is an 65 expansive spring, *l*, between the collar *4* of the spindle and the ring *3*, so that by forcing the collar *4* away from the ring *3* the shaft *h* will be moved endwise, and the pin *2* holding the inner end of the spring-jaws *k*, the flaring end 70 of the spindle causes the spring-jaws to close upon any article, such as a button, and hold the same.

The reverse movement opens the jaws by an end movement given to the spindle to draw its flaring end away from the spring-jaws. There is a neck at 5 around the spindle, near its back end, and also an annular flange, *m*, upon the frame *a*, within which the spindle-necks are contained. This annular flange *m* is made 80 thicker or bent backwardly at one place, to come into contact with the spindle when it is not being revolved, and, acting within the neck against the head of the spindle, draws the spindle back enough to allow the clamping-jaws 85 to open and liberate the buttons, and the jaws are held open long enough to allow another button to be placed into the jaws.

It is preferable to have the inner end of the spindle pointed, so that it will bear against 90 the bottom of the annular groove in which the ends of the spindles travel, except where the cam part of the flange acts to open the clamp or chuck.

All the spindles of the circular range are 95 constructed and operate in the manner described.

Upon the end of the shaft *b* there is a face-cam, *n*, with as many inclined faces, similar to saw-teeth, as there are spindles in the circular range, and upon the shaft *b* there is a corresponding but reversed cam, *o*, within which

the shaft *b* turns, the cam being kept from turning by a pin, *6*, in the slotted standard *r*, and there is a spring, *s*, acting against *o* to press it against *n*. Hence as *n* is revolved with 5 the shaft *b* it presses the cam *o* back on the shaft *b*, and as the teeth clear each other the cam *o* is moved forward by the spring *s*.

A similar movement is also given to the tool-carrier *t*, that has an eye around the shaft *b*, 10 and is between the cam *o* and the spring *s*. By this movement the tools that are carried by the tool-carrier *t* are pressed toward the buttons, and then moved back out of the way and brought around to the next button in the 15 range.

In order to cause the tool-carrier and tools to move partially around at the same rate of revolution as the heads *e e'* and occupy the proper place while acting upon the buttons, I 20 provide the studs *v* upon the head *e*, corresponding in number with the spindles, and upon the tool-carrier there is a stud, *w*, the position of which is such that when the cam *o* is moved endwise of the shaft *b*, as afore- 25 said, the stud *w* will be moved in between the studs *v*, and the next one of those studs coming along presses against the stud *w* and moves the same and the tool-carrier around with it at the same speed as the heads *e e'*, so that 30 the tools that are carried by the carrier *t* remain in the proper position to the buttons while being pressed up to their work.

As the tool carrier is moved the spring 10 is strained, and as soon as the teeth of *o* separate from *n* the spring *s* moves the cam *o* endwise of the shaft *b*, separating the studs *v* and *w*, and then the spring 10 returns the parts to their place of beginning.

The tools that are sustained and moved by 40 the tool-carrier will be constructed according to the work to be done. At 12 there is a cutter to groove the surfaces of the buttons, and at 13 and 14 there are polishing-brushes. These act in succession upon the buttons as 45 brought around by the revolving heads and revolved by the spindles.

In Fig. 4 I have shown the arrangement of drills that may be used to bore two or more holes in the buttons before the turning or 50 polishing. In this case the spindles *h* should be held, in order that the drills, which are not on the center line of the spindles, may act at the proper places and bore the holes in succession in the correct positions. The drill 14 bores 55 the hole in the blank Fig. 5; the drill 15 bores the second hole in the blank Fig. 6; and if there are other holes to be provided the drills 16 and 17 bore the holes in the positions indicated by corresponding numbers in Figs. 7 60 and 8.

It is to be understood that the heads *e e'* will have to be larger and the number of spindles increased sufficiently to allow the boring operations to be performed while the spindles 65 are not revolved in the heads; and in order to hold the spindles there should be a lever-

clamp, 20, on the head *e* adjacent to each spindle, with a spring end that is pressed upon by coming into contact with a stationary segmental fence, 21. When the movement of the 70 heads *e e'* carries the lever-clamp beyond 21 the spindle is relieved and ready to be revolved by the belt.

The tool-carrier shown in Fig. 4 for the boring tools or drills is an extension of or else 75 permanently connected to the tool-carrier *t*, and it receives the same movements, so that the drills are pressed to the buttons while the tool-carrier and heads *e e'* are moving together, and the drills are moved away from 80 the buttons by the tool-carrier, and then turned back to operate upon the next buttons in the circular range, the same as the other tools. In Fig. 4 a portion of the tool-carrier *t* is represented as broken off to show the studs *v* 85 and *w*.

I am aware that a machine has been made for polishing buttons containing a revolving head with a circular range of spindles driven by gearing.

In my machine the spindles are driven by 90 a belt, so that the spindles may not be acted on by the belt during a portion of the time that they are being carried around by the head. This allows the buttons to be introduced and withdrawn with facility or bored, and a high velocity can be given to the spindles while being rotated to render the polishing and finishing operations more perfect and rapid.

I claim as my invention—

1. A shaft revolved progressively and the heads *e e'* upon the same, in combination with the spindles *h*, placed in a circular range, the pulleys *h'* of the spindles, and the driving-belt *g*, substantially as set forth.

2. The circular range of spindles, each provided with a clamping-chuck, in combination with mechanism for revolving the spindles, tools for acting upon the buttons or other articles, a tool-carrier, and mechanism, substantially as specified, for moving the tools toward the buttons, and also moving the tool-carrier around with the heads that carry the circular range of spindles during the time that the 115 tools are in operation, then moving them away from the buttons and bringing them back to the place of beginning, substantially as set forth.

3. The combination, with the heads *e e'*, circular range of spindles *h*, and tool-carrier *t*, of the cams *n* and *o*, and studs *v* and *w*, and springs *s* and 10, substantially as set forth.

4. The combination of the revolving spindle *h*, clamping-jaws *k*, spring *l*, ring *3*, and annular flange *m*, substantially as set forth.

Signed by me this 28th day of November, A. D. 1879.

ALLEN NEWHALL.
